UNITED STATES PATENT OFFICE.

WILLIAM McCLELLAN AND THOMAS LEE McCLELLAN, OF LOS ANGELES, CALIFORNIA.

INDIVIDUAL-TOWEL RACK.

1,124,931.

Specification of Letters Patent.

Patented Jan. 12, 1915.

Application filed July 7, 1913. Serial No. 777,653.

To all whom it may concern:

Be it known that we, WILLIAM McCLELLAN and THOMAS LEE McCLELLAN, citizens of the United States, residing at Los Angeles, in the county of Los Angeles, State of California, have invented new and useful Improvements in Individual-Towel Racks, of which the following is a specification.

10 This invention relates particularly to a rack adapted for holding a supply of individual towels both before and after use; and its object is the provision of a simple, inexpensive and efficient form of rack on 15 which the towels may be easily placed and removed, and which will hold the towels in convenient position for use, allowing the soiled towels to be dropped and held separately from the fresh towels; and it is the 20 particular object of the invention to provide a means to hold the towels at all times against unauthorized removal.

Heretofore, one of the great objections to individual towel service has been the 25 prevalent loss of the towels; and the practical and economic supply of individual towel service depends largely upon the use of a device which will prevent the loss of towels, and which will at the same time provide a convenient support for the towels in 30 use. In fulfilling this requirement, the present invention embodies the combination of a suitable stand upon which a pile of towels may be placed, and a novel form of means 35 engaging each towel through a perforated or eyelet end. Said means preferably including a flexible vertically extending member down which the towel may drop after having been used, and upon which all the soiled 40 towels will hang until removed. The particulars of these various features we will explain in the following specification and the preferred forms will be shown in the accompanying drawings, in which:

45 Figure 1 is a perspective showing the improved towel rack. Fig. 2 is a detail section showing the construction of the towel holding means.

In the drawings the numeral 10 designates 50 a horizontal shelf or base upon which a pile of towels 11 is placed. The shelf may have a back 12 constructed in any suitable manner, either in the simple form illustrated, or the back may embody the usual mirror and 55 brush and comb and soap racks, or any other conveniences which may be desired. The

rack is preferably made to hang upon the wall; but may be secured to the wall in any preferred manner. Extending downwardly from the rear of the shelf there is a vertical member 13 which carries at its lower end a staple ring or other equivalent 14 adapted for engagement by the suitable lock 15. It will be understood that this staple and lock form the preferred means 60 for locking the end of the flexible member 16, which is preferably provided in the form of a suitable chain. The upper end of this chain 16 is secured to the end 17^a of a rod 17, swivelly supported in a tube 70 or sleeve 18 substantially in the manner illustrated. This tube or sleeve 18 is mounted in an upright position on the shelf 10, preferably through the medium of a flange 19; and the rod 17 may project slightly below the shelf 10 as is shown in Fig. 2. The upper end of the rod 17 has a curved portion 75 17^b which is free to swing around the vertical portion of the rod 17 as an axis. The chain 16 hangs somewhat loosely from the 80 end of the rod 17^a; but the chain is of such length that, when it is locked at its lower end, it is impossible to pull the rod 17 upwardly out of the tube 18.

The pile of individual towels is placed 85 upon the shelf 10; and each towel has a perforation or eyelet 11^a in one corner. The towels are folded somewhat as illustrated so that each of the eyelets may be slipped over the tube 18 as shown. As the towels 90 are used they are taken one by one off the pile of towels, and the action of picking up each towel causes its eyelet to slip up over the curved portion 17^b of the rod 17. When the towel has been used and is dropped it 95 slips down the chain 16 and hangs from the lower part of the chain. The soiled towels may be removed at any time by releasing the lock 15, when all of the towels on the chain may be readily slipped off. By releasing the 100 chain 16, the rod 17 may be removed from the tube 18; and then a new supply of towels is easily slipped over the tube 18. The rod 17 is then released and the chain 16 again locked in position.

105 From the foregoing, it is seen that the present invention supplies a simple and efficient means for supporting individual towels ready for service and for holding them after service and for preventing loss of towels. The rod 17 with its flexible member 16 is the particular feature of the com-

bination wished to be especially pointed out; and it is to this feature that the following claims are particularly drawn.

Having described a preferred form of our 5 invention, we claim:

1. In combination, a towel support, a vertical hollow standard permanently mounted on the support over which standard perforated towels may be placed, a rod 10 in said standard adapted to be removed therefrom by upward movement, and a flexible member attached to the upper end of the rod and releasably locked below in such 15 position that the rod cannot be moved upwardly to be removed from the standard except by releasing the lower end of the flexible member.
2. In combination, a towel support, a vertical tube mounted upon said support over 20 which perforated towels may be placed, a rod in said tube adapted to be removed therefrom by upward movement, the upper end of the said rod being curved laterally and downwardly, and a flexible member se- 25 cured to the curved end of the said rod and extending downwardly therefrom, and releasable locking means for securing the lower end of said flexible member against movement with respect to said tube, the 30 length of said member being such that its lower end must be released in order to raise the rod out of the standard.
3. In combination, a towel support, an upright tube mounted upon said support

over which tube perforated towels may be 35 placed, a rod swivelly supported in said tube and having a curved upper end, a chain at- 40 tached at its upper end to the curved end of said rod, and extending downwardly therefrom to a point below the support, and 45 releasable locking means for the lower end of the chain to secure that lower end against movement with respect to the tube, the chain being normally loose and flexible, and be- 50 ing of such length as to prevent the re- 55 moval of the rod from the tube.

4. In combination, a support, a vertical standard permanently mounted on said sup- 55 port, a rigid elongate member slidable ver- 60 tically with reference to said standard, said member being removable from said stand- 65 ard by upward movement, a flexible member attached at its upper end to the upper end of said rigid member and depending there- 70 from, and releasable locking means for the lower end of the flexible member to hold the lower end of that member in such posi- 75 tion that said rigid member may not be moved upwardly to be removed from the standard.

In witness that we claim the foregoing we have hereunto subscribed our names this 30th day of June 1913.

WILLIAM McCLELLAN.
THOMAS LEE McCLELLAN.
